[57] ABSTRACT

A microfiche duplicator adapted to make single or multiple copies of an original microfiche sheet using roll or sheet supply diazo or vesicular films, with the former developed by the use of either an aqueous or anhydrous developing agent, and providing automatic registration, handling and separation of original and copy sheets in which the original microfiche as well as copies thereof are conveniently returned to the front of the apparatus.

FIG 31

1
MICROFICHE DUPLICATOR

BACKGROUND OF THE INVENTION

1. Field of the Invention

The present invention relates generally to microscopy apparatus and more particularly to a new, improved and highly versatile microfiche duplicator for conveniently and automatically making single or multiple film copies of an original microfiche sheet.

2. Description of the Prior Art

As a result of the growing volume of documentary material presently being stored in microfiche form, the need has arisen for a versatile microfiche copier which is both simple in design and operation, requires minimal operator maintenance, and has the capability of providing high quality single or multiple copies automatically.

A number of approaches have been taken in the past in an effort to meet this need and generally have proven satisfactory for their intended purpose. However, conventional microcopiers exhibit various disadvantages which have limited their utility and widespread acceptance. For example, conventional prior art copiers often require manual handling and registration of both master and copy sheets, rely upon complex master-copy separation apparatus, and involve intricate mechanical movement of both master and copy fiche during operation. Further, they are generally limited to the use of either cut sheet copy film or roll film (in which case considerable film is wasted) and are designed to process only one of the diazo and vesicular film types. Accordingly, typical prior art microfiche duplicators, while being generally complex, do not provide sufficient copy reproduction accuracy, efficiency and/or flexibility to establish their widespread acceptance and utility in the marketplace.

Thus, while the demand for an improved, automatic microfiche copier has existed for some time, a duplicator capable of effectively meeting consumer needs in the form of a simple, fast and reliable self-contained unit has heretofore been unavailable.

SUMMARY OF THE INVENTION

Accordingly, it is an object of the present invention to automatically and rapidly duplicate an original microfiche sheet.

Another object of the invention is to make microfiche copies from either diazo or vesicular type films.

It is another object of the present invention to feed a microfiche copier from a continuous roll of copy film which is premeasured and cut prior to exposure.

This invention has a further object in that a sheet of copy film is automatically registered and processed through exposure and development station without the need for manual handling.

A further object of the present invention is to construct a microfiche duplicator in which diazo and vesicular film types may be substituted for each other by merely repositioning a single selector switch.

This invention has a further object in that a copy sheet traverses a generally U-shaped path and is returned to a position adjacent the original sheet.

Another object of this invention is to employ an aqueous or anhydrous diazo developing agent in the developer unit of a diazo copier with equal facility.

2

The present invention is summarized in that a microfiche duplicator includes a frame, a copyboard movable on the frame between loading and exposing stations and supporting an original film sheet and a copy sheet in superposed relationship, a register assembly responsive to movement of the copyboard to the exposing station for registering the copy sheet with the original sheet, and exposure assembly for exposing the copy sheet through the original, a developing assembly for the exposed copy, an a separator for separating the exposed copy sheet from the original sheet and transporting the same to the developing assembly.

The present invention is advantageous over the prior art in that roll or sheet copy supply film may be utilized, diazo or vesicular type films may be supplied, copy and master sheets are automatically registered and handled during the duplication process, master and copy sheets are efficiently separated after exposure utilizing a minimum number of operative parts, and that original and copy fiche are conveniently returned to the front of the apparatus.

Other objects and advantages of the present invention will become apparent from the following description of a preferred embodiment when taken in conjunction with the accompanying drawings.

BRIEF DESCRIPTION OF THE DRAWINGS

FIG. 1 is a perspective view of a preferred embodiment of a microfiche duplicator in accordance with the present invention;

FIG. 2 is a front elevational view of the duplicator of FIG. 1 with parts broken away;

FIG. 3 is a right side elevational view of the duplicator of FIG. 1 with parts broken away;

FIG. 4 is a rear elevational view of the duplicator of FIG. 1 with parts broken away;

FIG. 5 is a left side elevational view of the duplicator of FIG. 1 with parts broken away;

FIG. 6 is a side elevational view of the film feed and cutter assembly of the duplicator of FIG. 1;

FIG. 7 is a rear elevational view of the film feed and cutter assembly of FIG. 6;

FIG. 8 is a front elevational view of the film feed and cutter assembly of FIG. 6;

FIG. 9 is a plan view of the copyboard assembly of the duplicator of FIG. 1;

FIG. 10 is front elevational view of the copyboard assembly of FIG. 9;

FIG. 11 is a left side elevational view of the copyboard assembly of FIG. 9;

FIG. 12 is a right side elevational view of the copyboard assembly of FIG. 9;

FIG. 13 is a sectional view in detail taken along line 13-13 of FIG. 9;

FIG. 14 is a plan view of the exposure and clearing assembly of the duplicator of FIG. 1;

FIG. 15 is a front elevational view of the exposure and clearing assembly of FIG. 14;

FIG. 16 is a left side elevational view of the exposure and clearing assembly of FIG. 14;

FIG. 17 is a right side elevational view of the exposure and clearing assembly of FIG. 14;

FIG. 18 is a plan view of the exposure lamp and reflector assembly of the duplicator of FIG. 1;

FIG. 19 is a side elevational view of the lamp and reflector assembly of FIG. 18;

FIG. 20 is a diagrammatic view in elevation of the exposure and clearing assembly of FIG. 14 in a first position;

FIG. 21 is a diagrammatic view similar to FIG. 20 showing the exposure and clearing assembly in a second position;

FIG. 22 is a diagrammatic view in section of the exposure and clearing assembly and developing assembly of the duplicator of FIG. 1;

FIG. 23 is a diagrammatic view of the sheet separation assembly of the duplicator of FIG. 1 in a first position;

FIG. 24 is a diagrammatic view similar to FIG. 23 showing the sheet separation assembly in a second position;

FIG. 25 is a diagrammatic view similar to FIG. 23 showing the sheet separation assembly in a third position;

FIG. 26 is a side elevational view of the developing assembly of the duplicator of FIG. 1;

FIG. 27 is an elevational view partly in section taken along line 27-27 of FIG. 26;

FIG. 28 is a sectional view of the developer belt sub-assembly of the developing assembly of FIG. 26;

FIG. 29 is a detailed elevational view of the liquid metering assembly of the duplicator of FIG. 1 in a first position;

FIG. 30 is a detailed view similar to FIG. 29 showing the liquid metering assembly in a second position;

FIG. 31 is a detailed view similar to FIG. 29 showing the liquid metering assembly in a third position; and

FIG. 32 is a side elevational view of the liquid metering assembly of FIG. 29.

DESCRIPTION OF THE PREFERRED EMBODIMENT

A preferred embodiment of a microfiche duplicator in accordance with the present invention is illustrated in FIG. 1 and is housed in a cabinet structure indicated generally at 10 having a base 12 in the form of a hollow cabinet supported upon legs 14. Mounted atop the base cabinet 12 is a main housing 16 divided into a reproduction compartment 18 and a control and supply compartment 20. The reproduction compartment 18 houses the main reproduction apparatus of the duplicating machine and may be provided with any number of suitable removable cover assemblies such as side and top covers 22 and 24. Cover 24 is designed to expose the copyboard assembly 26 for the reproduction apparatus to be described below such that an original microfiche sheet may be conveniently placed atop the copyboard at the beginning of a copy sequence. The remaining reproduction apparatus is shielded from view to present an aesthetically pleasing appearance complementary to the office area where it is to be used.

A main control panel 28 is disposed on the front of the control and supply compartment 20 and facilitates the operation and sequence selection of the machine. As will be described in detail below, the control panel 28 houses all controls with the exception of a single-multiple selector switch and a diazo-vesicular selector switch, both of which are located within a film supply area enclosed within compartment 20 and accessed by the opening of a hinged front door panel 30.

Before proceeding with a detailed description of the various systems and sub-systems embodying the duplicating apparatus according to the present invention, a

brief general description of the operation of the assembly will be presented for purposes of clarity.

The duplicator is turned on by depressing the appropriate switch on control panel 28 whereupon the apparatus readily assumes a stand-by or ready mode for the initiation of a reproduction sequence. The ready state is indicated by the ignition of a suitable lamp on control panel 28, and thereafter an operator may conveniently insert an original microfiche sheet 32 atop the copyboard 26. With the microfiche 32 manually placed approximately in the proper position for reproduction, a sequence initiation switch on panel 28 is actuated causing a preselected length of copy film to be advanced from a bulk film roll located within the housing behind panel 30. After the preselected length of film has been taken from the film supply roll, the copy sheet is severed and falls atop the original copy of copyboard 26.

With the above steps completed, the copyboard assembly 26 is automatically sequenced to begin movement toward the rear of the machine, which movement causes the original and copy microfiche sheets to be brought into precise registration. As the copyboard 26 advances rearwardly, the copy sheet is exposed through the original until the entire exposure has been made. With the copyboard continuing its rearward movement, the copy sheet is automatically separated from the master or original and continues its rearward movement beyond the exposure station and into a development chamber. As the copy sheet advances through the development chamber, the original is brought back to the front of the duplicating machine by a rapid forward movement of the copyboard back to its original loading position.

The copy sheet continues its advancement through the developing chamber which is constructed in a generally U-shaped configuration such that the copy sheet exits from the developing chamber in a forward-going direction toward the front of the apparatus. The copy sheet then passes through a clearing station which is activated only when vesicular type copy films are used and is placed in a passive or stand-by mode for conveyance purposes only when diazo films are employed. The copy sheet is then received in a collection tray 34 located under the loading station or initial position of copyboard 26 and the sequence is completed. If it is desired to make multiple copies of an original microfiche sheet, the above process may be repeated by selection of the appropriate control on panel 28 with more than one copy sheet being fed through the equipment at any one time as the copyboard moves back and forth between loading and exposure stations. As will become clear as the description proceeds, the apparatus in accordance with the present invention has the capability of making not only single or multiple copies but further may utilize diazo or vesicular film types developed in the case of diazo film with an aqueous or anhydrous developing agent supply.

FILM FEED AND CUT-OFF ASSEMBLIES

Referring now to FIGS. 2 and 5 through 8, door 30 of the control and supply compartment 20 provides access to an area 36 in which is supported a roll of suitable copy film 38 upon a reel 40, which is journaled for free rotation about a horizontal, longitudinally disposed shaft 42 affixed to a frame member (not shown) at the rear of area 36. As will be more fully described

below, the film 38 may be of either diazo or vesicular type in a width corresponding to the width of the original microfiche sheet to be duplicated.

The end of the film supply roll 38 is fed through a film advancing assembly indicated generally at 44, past a cutting assembly indicated generally at 46 to an area above the copyboard plate 26. In this manner, the film may be advanced from the roll 38 by assembly 44 whereupon it is thereafter cut by the cutting assembly 46 such that the severed copy sheet section will fall in approximate alignment with the master or original microfiche sheet on the copyboard 26. As shown in FIGS. 1 and 2, the top cover 24 of the reproduction compartment 18, may be provided with an elongated rectangular lip 48 designed to fit over and cover the cutting assembly 46 for safety and aesthetic purposes.

The film advancing and cutting assemblies 44 and 46 are shown in detail in FIGS. 6, 7 and 8, and include a generally U-shaped frame 50 having rotatably secured thereon a metering roller 52 constructed of a suitable non-compressible material such as steel or aluminum and having its shaft protruding through the rear wall of frame 50 and terminating in a gear 54. A second roller 56 is constructed of a resilient, compressible material such as rubber and is disposed with its shaft aligned in parallel with the shaft of roller 52. The left end of the shaft of roller 56 as visualized in FIG. 6, is rotatably secured in the bifurcated end of a connecting member 58 (FIG. 7) fixedly secured through a rotatable rod 60 to a generally L-shaped link member 62 having a first leg bifurcated at its distal end for supporting the right side or end of the shaft of roller 56 as illustrated in FIG. 8. The second leg of L-shaped member 62 has formed on its distal end a flat spring retaining plate 64 which cooperates with a compression spring 66 and a bolt 68 mounted on a threaded opening in the frame 50 to cause member 62 to be biased in a counter-clockwise direction as viewed in FIG. 8 thereby holding roller 56 firmly against roller 52 for capturing the end of film roll 38 therebetween.

The left end of the shaft of roller 56 terminates in a gear 70 which cooperates with gear 54 of shaft 52 to provide proper rotation of both rollers during the film advancing sequence. The right hand end of the shaft of roller 56 protrudes through the front wall of the frame 50 and is adapted to carry a suitable knob 72 thereon to facilitate the manual advancement of the copy film from roll 38. A second elongated knob 74 is disposed on the end of a short shaft 76 carrying a cam member 78 (FIG. 8) constructed to cooperate with the first leg of L-shaped member 62 such that when the knob 74 is in the position illustrated, L-shaped member 62 is freed to bring roller 56 firmly against roller 52 under the force of spring 66. Further, the knob 74 is rotated in a counter-clockwise direction through an arc of approximately 180°, a protrusion 80 on the peripheral surface of cam 78 engages the underside of L-shaped member 62 to swing the same clockwise against the force of spring 66. Roller 56 is thereby moved away from roller 52 disengaging the copy film and facilitating the threading of the end of a replacement copy roll as necessary.

In addition to the metering and advancing rollers 52 and 56, guide means in the form of a generally flat plate 82 having a downwardly curved front edge and laterally upright front and rear flanges is provided on frame 50 to direct the end of the film roll 38 into the film feed

and cutting apparatus. Further, an exit guide plate 84 is mounted to the frame just beyond rollers 52 and 56 and is constructed in the form of a flat plate having a generally L-shaped cross section with a pair of laterally protruding, downwardly inclined, guide tabs 86 and 88 formed on the lower corners thereof to maintain the central disposition of the film end as it passes beyond the rollers 52 and 56.

A drive motor 90 is mounted atop frame 50 and has a shaft 92 disposed longitudinally of the duplicating apparatus and extending from the front and rear sides of the motor. A cooling fan 94 is mounted on the front end of shaft 92, and the rear end of shaft 92 applies motive power to the film feed apparatus through suitable gear transmission 96. The output shaft 98 of transmission 96 has mounted on its rear end a cam wheel 100 of generally circular configuration with a camming protrusion 102 formed in the peripheral surface thereof as illustrated in FIG. 7. A drive block 104 of generally rectangular configuration is affixed to wheel 100 and is connected through a journaled connector block 106 disposed at a point adjacent the periphery of wheel 100 to a drive chain 108. Chain 108 passes around the sprocket of a dual gear assembly 110 having its larger gear disposed in engagement with gear 54 of roller 52. The opposite end of chain 108 is connected to the frame of the duplicating apparatus by a spring 112 to maintain the chain in tension at all times during operation of the film feed apparatus 44.

Referring to FIG. 7, it can be appreciated that as motor 90 drives wheel 100, block 104 traverses a 360° path causing chain 108 to be extended during the first 180° of movement and thereafter released to assume its rest position as shown. The movement of chain 108 to its extended position causes gear assembly 110 to be rotated counter-clockwise thereby advancing rollers 52 and 56 a precise amount to feed a preselected length of film from roll 38. Gears 54 and 70 are each coupled to rollers 52 and 56, respectively, by a suitable one-way clutch such that the rollers are only rotated in a direction to cause advancement of the end of film roll 38 by gear assembly 110. Thus, while gears 54 and 70 are free to rotate in both clockwise and counterclockwise directions, the clutches associated therewith only transmit motive energy to the rollers in the film advancing direction. An additional clutch 113 on the opposite end of roller 52 serves to preclude reversal rotation by the rollers during the second 180° movement of cam wheel 100.

As shown in FIGS. 6 and 7, first and second microswitches 114 and 116 are affixed to frame 50 with their contact arms 118 and 120, respectively, riding upon the peripheral surface of cam wheel 100. As will be fully described below, micro-switch 114 functions to de-energize motor 90 after its actuating arm 118 rides up from the main circular surface of wheel 100 onto the cam protrusion 102. Thus, upon energization of motor 90, cam wheel 100 will traverse a single 360° revolution coming to rest in the position illustrated in FIG. 7 as cam protrusion 102 engages arm 118 of switch 114. Also, as wheel 100 traverses its single revolution, cam protrusion 102 will momentarily actuate micro-switch 116 through arm 120 to register a count corresponding to the advancement of a single sheet of copy film. Thus, the film feed assembly 44 provides precise advancement of a preselected length of copy film from roll 38, registers the count thereof, and as-

sumes a steady state as shown in FIG. 7 upon the completion of a single copy sheet advance movement.

The cutting assembly 46 is also mounted on frame 50 and includes a main cutting blade in the form of a flat plate 130 having a beveled bottom edge 132 which cooperates with a fixed cutting bar 134 on frame 50. Blade 130 is affixed to a carrier plate 136 which is pivotally attached at its upper end within the bifurcated end of an arm 138 of a generally L-shaped cutter drive member 140. L-shaped member 140 is journaled for rotation about a shaft 141 disposed longitudinally of the duplicating apparatus and mounted on the upright arms of frame 50 as shown in FIG. 6. The carrier plate 136 is biased with respect to arm 138 by a pair of compression springs 142 nested within recessed openings in the upper side surface of plate 136 and a spring retaining bar 144 carried on arm 138. In this manner, the cutter plate 130 is biased against the cutting surface of blade 134 such that as the plate 136 is shifted downwardly the film roll end will be severed to provide the desired, premeasured copy sheet.

The second arm 146 of L-shaped member 140 supports a roller bearing 148 for engagement with a generally elliptical cam 150 which is also driven on the shaft 98 of transmission 96 from motor 90. A pair of springs 152 and 154 are mounted in tension between the top of frame 50 and the distal end of arm 138 of L-shaped member 140 to bias the same upwardly thereby withdrawing the cutting blade 130 away from bar 134 and maintaining roller bearing 148 in direct contact with the peripheral surface of cam 150 during the film advance and cutting sequence.

Thus, upon initial energization of motor 90, shaft 98 drives cams 100 and 150 for respectively advancing the film end through rollers 52 and 56 and thereafter rotating member 140 to shift the cutting blade 130 downwardly against cutting plate 134 to sever the measured film length from the supply roll. As noted above, the film feed assembly 44 and cutter assembly 46 are both placed in a stand-by or ready state upon the completion of a single film sheet advance, facilitating the making of any number of desired copies as the duplicator sequence proceeds.

COPYBOARD AND FILM REGISTRATION ASSEMBLY

Referring to FIGS. 9 through 13, the copyboard assembly includes an ultraviolet transmissive plate 26 which may be made of any suitable material such as treated or coated glass designed to pass ultraviolet radiation from the exposure source of the duplicating system to the original and copy sheets resting atop the plate 26. It is also preferred that plate 26 be designed to filter as much as possible of the unwanted radiations emitted from the ultraviolet source as well as heat so as to prevent damage or deterioration of the film sheets during the duplicating process. Plate 26 is attached in an opening 200 defined by a generally rectangular copyboard housing 202 having a downwardly extending flange 204 along its left side supporting at spaced points a pair of roller bearings 206 and 208. Bearings 206 and 208 are adapted to ride along an elongated guide rail 210 (FIG. 15) mounted upon a frame member to be described below. Guide rail 210 may be of any suitable design and is preferably square in cross section as shown in FIG. 15. A micro-switch trip bar 212 having a pair of protrusions 214 and 216 formed

on the ends thereof is also affixed along the lower edge of side flange 204 as visualized in FIG. 11.

A pair of linear bearings 218 and 220 are suitable attached to the right hand side of the copyboard 202 and ride along a shaft 222 fixedly secured to the frame of the duplicator housing in a longitudinal horizontal position as illustrated in FIG. 15. Attached to the top of copyboard housing 202 is a generally L-shaped fixed left side stop 224 and a suitable clamp plate 26. Also, a forward edge stop assembly, indicated generally at 236 and mounted on copyboard housing 202, includes a pair of parallel arms 228 and 230 pivotally mounted at one end to the copyboard at points 232 and 234 and similarly pivotally mounted at their other ends to an adjustable carriage plate 238. Plate 238 supports a compressible, rectangular sheet of material such as a foamed plastic or rubber composition 240 having disposed on its upper surface a thin semi-rigid sheet of plastic 242. The edge of plastic sheet 242 closest to the copyboard plate 26 overhangs the compressible element 240 by a slight amount, such as an eighth of an inch, so that the forward edge of an original microfiche sheet may be placed under the top sheet 242 and against the front side surface of element 240. The aforementioned structure is illustrated diagrammatically in FIGS. 23, 24 and 25. A spring 239 is held in compression between the copyboard housing 202 and the slotted right end of carriage plate 238 causing the same to be biased toward the end of a screw 241 adjustably positioned by the rotation of a knob 243. In this manner, the longitudinal position of assembly 236 with respect to copyboard plate 26 may be readily adjusted by rotating knob 243 thereby swinging the parallelogram formed by arms 228 and 230 and carriage plate 238 in the plane of the copyboard housing 202.

To facilitate the insertion of an original microfiche sheet atop the copyboard plate 26, a pair of front stop members 244 and 246, each having a pair of spaced, upright tangs, are attached to a rotatable shaft 248 journaled on the copyboard assembly under the copyboard housing 202. Shaft 248 extends through the side flange 204 and terminates in a rectangular arm 250 which cooperates with a spring 252 to bias the shaft 248 for rotating stop members 244 and 246 to an upright position shown in FIG. 1. Also disposed between the upright tangs of each of the stops 244 and 246 are angulated retaining members 254 and 256 which ride within grooves 258 and 260, respectively, in the copyboard housing 202. In this manner, engagement of the upper end of arm 250, as the copyboard housing 202 moves linearly toward the rear of the duplicating apparatus, causes the rotation of shaft 248 and the retraction of stop members 244 and 246 into a pair of accommodating recesses in the housing surface. At the same time, retaining members 254 and 256 are swung back and down to nest between the tangs of the stop members such that both front stop assemblies are withdrawn from their biased upwardly protruding positions as shown and brought flush with the surface of housing 202.

An elongated lever 262 of generally L-shaped cross section is connected to the front of the copyboard assembly housing 202 at each end by members 264 (FIG. 13) and 266 (FIG. 12) which are pivotally secured to the underside of the copyboard housing 202. Referring to FIG. 13, members 164, which is disposed on the left side of lever 262 is visualized in FIG. 9, is pivotally

mounted at point 268 and is connected through an arm 270 and a pin 272 to a triangular link 274 rotatable about pivot 276. Link 274 is biased to the position illustrated in FIG. 13 by spring 278 and defines a slot 280 which accommodates pin 272 of arm 270. The apex of link 274 is pivotally secured to a rectangular link member 282 defining a slot 284 accommodating the pin 286 of a generally triangular eccentric arm 288 fixedly secured to the shaft 248 of stop members 244 and 246. Eccentric 288 assumes a rest position as illustrated in FIG. 13 which may be adjusted by the setting of a small screw 290 through the copyboard housing 202.

In operation, downward pressure exerted upon lever 262 as by the hand of an operator causes the rotation of member 264 about point 268 in a counter-clockwise direction. The counter-clockwise movement of member 264 is transmitted to the triangular link 274 causing the same to rotate clockwise about pivot 276. Link member 282 is thus moved rearwardly to rotate the eccentric member 288 counter-clockwise thus rotating shaft 248 and causing the retraction of stop members 244 and 246 as previously described. In this manner, at the start of a reproduction sequence, an operator may merely depress lever 262 causing the aforescribed linkages to rotate shaft 248 and retract stops 244 and 246 so as to facilitate the insertion of an original microfiche sheet with the leading edge thereof resting against the compressible member 240 under the overhanging front edge of plastic sheet 242. Thereafter, lever 262 may be released whereby stops 244 and 246 revert to their biased upright positions so as to properly orient the original microfiche sheet longitudinally of the copyboard housing 202. Further, as the original microfiche sheet is placed by an operator atop plate 26 adjacent left fixed stop 224, the duplicator according to the present invention will automatically thereafter provide positive lateral alignment of the original sheet by the operation of a pair of laterally movable right stops 292 and 294.

Referring to FIGS. 12 and 15, stops 292 and 294 protrude from the upper surface of a generally Z-shaped bent plate 296 which has secured centrally thereto an elongated collar 298 which is journaled for rotation about a shaft 300 suitably affixed to the copyboard housing 202. Plate 296 is biased by a spring element 302 in a counterclockwise direction as visualized in FIG. 15 thus tending to bring stop members 292 and 294 to an upright position against a pair of recesses 304 and 306 formed in the copyboard plate 26. A cam roller 308 is centrally disposed upon the lower distal arm of member 296 and cooperates with a linear cam 310 for rotating member 296 and thus causing the movement of stops 292 and 294 with respect to the fixed left stop member 224 as the copyboard assembly moves along its linear path of travel. As shown in FIG. 17, cam 310 has a generally flat surface 312 and a flat recessed surface 314 such that stop members 292 and 294 are normally held in a position away from left stop member 224 and move toward stop 224 as roller 308 rides along cam 310 and into recess 314.

A gear rack 320 is attached along the right side of copyboard housing 202 and cooperates with a circular gear 322 which is driven through a slip clutch 324 by a reversible DC motor 326. Motor 326 is attached at plate 328 to the frame member of the exposure assembly to be described below. Thus, as the DC motor 326 rotates gear 322, the copyboard assembly is moved lin-

early along a longitudinal path on roller bearings 206 and 208 and linear bearings 218 and 220.

In operation, after an original microfiche sheet has been inserted over the copyboard plate 26 as described above, a preselected length of copy film is supplied by the film feed and cutting assemblies 44 and 46 and falls atop the original sheet on the copyboard housing 202. Thereafter, actuation of DC motor 326 causes the copyboard assembly to move linearly toward the rear of the duplicator whereupon roller 308 rides along cam 310 into recess 314 causing the rotation of stops 292 and 294 toward the fixed left stop 224 to move both the original and copy sheets against the stop member 224 for precise lateral registration thereof. As will be more clearly appreciated as the description proceeds, after roller bearing 308 traverses the recessed groove 314 in cam 310 it will ride up onto surface 312 thereby retracting stops 292 and 224 from interference with the exposure roller (to be described below) as the copyboard assembly continues its rearward movement. Likewise, an elongated rectangular cam 330 affixed to the left side of the frame of the exposure assembly cooperates with arm 250 of shaft 248 such that the same engages cam 330 and is rotated thereby as the copyboard moves through the exposure station for retracting upright stops 224 and 246 to preclude damage to the exposure assembly as the copyboard completes its rearward movement.

Also carried on the copyboard housing 202 is a flat guide plate 332 and a linear cam 334 aligned longitudinally along the left edge of the housing 202 and similar in configuration to that of linear cam 310. Cam 334 thus defines a main, flat cam surface 336 having formed therein a notch-like recess 338 for cooperation with the roller bearing of a copy sheet pick-off assembly to be described below. In addition, the forward edge portion of copyboard housing 202 is tapered at surface 340 (FIG. 12) adjacent guide plate 332 for cooperative engagement with a soft pressure roller on the rearward pass of the copyboard assembly during a reproduction sequence.

EXPOSURE AND CLEARING ASSEMBLY

The exposure and clearing assembly of the duplicator according to the present invention is illustrated in FIGS. 5 and 14 through 17 and includes a frame formed of a base plate 398 having a pair of side plates 400 and 402 affixed thereto in spaced parallel relationship. Each of the side plates 400 and 402 is generally rectangular in configuration and has a pair of extension ears 404-406 and 408-410, respectively, extending orthogonally from an upper rear corner thereof. Guide rail 210 of the copyboard assembly is horizontally secured to frame plate 400 as shown in FIG. 15 as is the support rod 222 for linear bearings 218 and 220. Further, motor 326 for driving the copyboard assembly is attached at plate 328 by suitable means such as screws to the side plate 402 as shown in FIGS. 15 and 17. A suitable flat, rectangular plate 412 extends between and is rigidly secured to ears 406 and 410 of side plates 400 and 402, respectively, to provide the necessary structural rigidity for the entire frame assembly.

A soft roller 414, constructed of any suitable material such as solid or foam rubber, is mounted for free rotation about a transverse shaft 416 connected between plates 400 and 402. Roller 414 is disposed for engagement with the upper surface of the copyboard assembly

housing 202 as the same is moved rearwardly of the duplicating apparatus by motor 326 to maintain the original and copy microfiche sheets in firm contact against each other and against the surface of the copyboard plate 26 during movement of the same. Cooperating with the soft roller 414 is a copy film drag assembly which includes a generally curved support member 418 frictionally secured to the hub of roller 414 by a pair of spaced leg members 420 and 422. A stop member 424 protruding from the inside surface of flange 406 of frame side plate 400 cooperates with a recessed groove 426 in leg member 422 to define the limits of rotary movement of the drag cover 418. As shown in FIG. 15, a pair of thin, rectangular rubber strips 428 and 430 are secured to the lower front corners of member 418 and cooperate with the copyboard assembly and the soft roller 414 to engage the forward edge of a copy sheet and exert a drag force thereupon to shift the copy sheet against stop members 244 and 246 for precise longitudinal registration of original and copy sheets of microfiche as the copyboard assembly moves rearwardly of the duplicating apparatus. Also disposed on the front surface of member 418 is a centrally protruding nose 432 which gently engages the exposed surface of the copy sheet to correct for improper alignment caused by any film curl existing in the original or copy film sheets.

Thus, as the copyboard housing 202, containing both original and copy sheets, begins to move rearwardly of the duplicator, the inclined forward surface 340 of the copyboard housing will engage the peripheral surface of soft pressure roller 414 causing the same to be rotated as the copyboard continues its forward advancement. Since cover member 418 is in frictional engagement with the hub of pressure roller 414, the initial rotation of the roller caused by the movement of the copyboard housing rotates the cover in a clockwise direction as visualized in FIG. 16 to bring the rubber drag members 428 and 430 downwardly into contact with the top surface of the copyboard. At the same time, the protruding nose 432 of plate 418 swings down over the center of the advancing copy and original sheets flattening the curl thereof and gently urging the same against the surface of plate 26.

Upon continued rearward movement of the copyboard assembly, stop 424 engages the rear edge of groove 426 precluding further rotation of plate 418 as the pressure roller 414 continues to be moved by the advancing copyboard housing 202. The drag members 428 and 430 thereafter engage the forward edge of the copy sheet causing the same to be slid into engagement with stops 246 and 244 assuring precise registration of the copy sheet with the original microfiche carried by the copyboard. Further advancement of the copyboard assembly causes the registered copy and original microfiche sheets to be brought under the pressure roller 414 maintaining the microfiche sheets in firm contact with each other and with the top surface of the transmissive plate 26 for exposure of the copy sheet as will be described below.

A generally triangular flat copy sheet pick-off plate 450 is pivotally secured along its rear edge on a shaft 452 mounted between plates 400 and 402 of the exposure frame assembly. In this manner, the apex of the triangular plate 450 is centrally disposed with respect to the copyboard assembly and points to the front of the duplicating apparatus as illustrated in FIG. 14. A roller

bearing 454 is attached to the distal end of a linkage arm 456 having its proximal end rigidly secured to the triangular pickup plate 450 at its left side as viewed in FIG. 15. Roller bearing 454 cooperates with linear cam 334 carried upon the copyboard housing 202 to lift the apex of the triangular pick-off plate 450 slightly away from the copyboard surface until the forward edge of the copy sheet has just passed the pressure roller 414. Thereafter, roller bearing 454 will ride into recess 338 in cam 334 enabling the apex of the pick-off plate 450 to engage the top surface of the thin plastic sheet 242 covering the compressible sponge-like element 240. Since the forward edge of the original microfiche sheet is inserted below the overhanging edge of plastic sheet 242, and the copy microfiche sheet rests atop sheet 242, the apex of the pick-off plate 450 will cause element 240 to be compressed allowing the pick-off plate to ride under and lift off the forward edge of the copy sheet as the same is further advanced by the continued movement of the copyboard assembly. Also, as the roller bearing 454 rides out of the recess 338 and onto the surface 336 of cam 334, the apex of pick-off plate 450 is raised above the copyboard surface thereby lifting the copy sheet away from the original microfiche sheet to simply, effectively and positively separate the two as the copyboard housing 202 progresses to the rear of the duplicating apparatus.

As noted briefly above, after the copy sheet has been separated from the original, the exposed copy thereafter proceeds to a developing station while the original microfiche sheet is transported upon the copyboard back to the front of the duplicator. In order to preclude fouling of the original sheet upon the forward-going return of the copyboard assembly which, for example, may be caused by the presence of a fold or curl in the original microfiche sheet, an elongated rod-like retaining roller 458 is pivotally secured to the underside of the triangular pick-off plate 450 slightly below and parallel with shaft 452 to engage the original microfiche sheet and maintain the same in a generally flat posture upon the copyboard surface. Thereafter, as the copyboard carriage returns to its initial position, the roller 458 assures that the same will smoothly pass below the soft pressure roller 414 without becoming damaged.

An exposure lamp assembly indicated generally at 470 is disposed transversely of the duplicator apparatus between frame plates 400 and 402 and includes a base plate 472 of generally flat, rectangular configuration adapted to be slidably secured within grooves 474 and 476 formed in a pair of transverse mounting brackets 478 and 480, respectively, attached between plates 400 and 402. A generally L-shaped flange 482 is attached to base 472 and carries a threaded bolt 484 adapted to be cooperatively received within a mounting bracket 486 attached to plate 400. The exposure lamp assembly 470 is thus selectively removable and may be secured in position directly underneath the soft pressure roller 414 by sliding base 472 along grooves 474 and 476 and thereafter engaging bolt 484 with bracket 486. A rectangular opening is centrally defined by base plate 472 over which is disposed a light transmissive heat filter element 487 which may be constructed of any suitable material well known to those skilled in the art.

As shown in FIGS. 18 and 19, the exposure lamp assembly 470 additionally includes a pair of upright side flanges 488 and 490 connected with front and rear upright flanges 492 and 494 to form a generally rectangu-

lar box-like arrangement secured atop base plate 472. Side flanges 488 and 490 each include a generally rectangular lamp mounting plate 496 and 498, respectively, defining a slot 500-502 accommodating the ends of an elongated tubular ultraviolet lamp 504. Lamp 504 may be of any suitable construction and is preferably a 1,000 watt ultraviolet mercury vapor lamp having insulated terminal portions 506 and 508 adapted to be nested within the grooves 500 and 502 of brackets 496 and 498, respectively. Operating potential for lamp 504 may be supplied from a suitable power source (not shown) through jacks mounted upon the exposure and clearing assembly frame for cooperation with a pair of plugs 510 disposed upon the front flange 492 as shown in FIG. 18. Each of the two plugs 510 is connected through a respective standoff insulator 512-514 to the lead wires 516 and 518 extending from insulators 506 and 508 of the lamp.

A generally parabolic elongated reflector assembly is disposed under lamp 504 and includes a first polished metal reflector element 530 secured, as by screws, at its upper end to a lip 532 formed along the top edge of flange 494. A second polished metal reflector element 534 is secured through hinge 536 and suitable screws to a lip 538 formed along the upper edge of flange 492. Reflector element 534 is connected at its lower edge, as viewed in FIG. 18, through a pivot pin to a generally L-shaped connecting link 540 having the shorter arm thereof secured through tension spring 542 to the flange 492. A solenoid 544 is mounted by a bracket 546 to flange 492 and has its plunger 548 pivotally connected to the elbow of L-shaped link member 540 and receives a control signal at its winding through a pair of plugs 550 which cooperate with complementary jacks (not shown) affixed to the exposure assembly frame. In this manner, actuation of solenoid 544 causes the retraction of plunger 548 which acts through link member 540 to swing the reflector element 534 away from lamp 504 to allow ultraviolet radiation to pass through heat filter 487 for illuminating the upper surface of an endless conveyor belt 570.

Conveyor belt 570 is constrained between a pair of horizontally aligned spaced rollers 572 and 574 extending transversely between plates 400 and 402 and journaled for rotation thereupon. A gear 576 is attached to the inner end of roller 572 for cooperative engagement with a motor drive assembly to be described below. Conveyor belt 570 may be constructed of any suitable material such as rubber impregnated fiberglass and is maintained in its desired lateral position by a pair of inclined rollers 578 and 580 which are pivotally disposed upon angulated brackets 582 and 584, respectively, for engagement with the inner surface of belt 570 below rollers 572 and 574 as shown in FIG. 15.

An inverted generally U-shaped collimator support tray 590 is slidably disposed between frame members 400 and 402 above the exposure lamp assembly 470 for supporting a suitable honeycomb collimator between the ultraviolet lamp source 504 and the pressure roller 414. The honeycomb collimator 592 may be removed from its operative position between lamp 504 and roller 414 by longitudinal movement of tray 590, if desired.

An exhaust duct 594 of generally rectangular cross section extends laterally across the exposure and clearing assembly in front of the lamp assembly 470 and has suitable openings adjacent the lamp assembly for ex-

hausting the heated air surrounding the lamp from the apparatus. Duct 594 communicates through a circular connector 596 to an exhaust hose 598 connected with a blower to be described below. In addition, a pair of circular openings 600 and 602 in plate 402 communicate through first and second air hoses with a blower (described below) to supply cooling air to the conveyor belt 570 and the copyboard assembly 202, respectively.

10 A pair of microswitches 604 and 608 are mounted upon L-shaped brackets 610 and 612, respectively, secured to plate 400 of the exposure frame assembly such that the actuating arms of microswitches 604 and 608 protrude through openings in the plate wall for selective engagement and actuation by protrusions 214 and 216 carried on flange 204 of the copyboard assembly as shown in FIG. 11.

DEVELOPING ASSEMBLY

20 Turning now to FIGS. 5 and 26 through 28, the developing chamber for the duplicating apparatus of FIG. 1 is indicated generally at 700 and includes a generally U-shaped hollow housing 702 having a base portion 704 and a pair of upper and lower leg portions 706 and 708, respectively. The developing chamber 702 is mounted to the frame of the duplicator on a pair of spaced legs 710 and 712 such that the upper and lower leg portions 706 and 708 are in horizontal superposition as illustrated in FIG. 5. A generally rectangular developing-agent receiving tray 714, open at its upper end, is centrally affixed to the floor of lower leg 708 such that the interior of tray 714 communicates interiorly of chamber 702 through an opening 716 in the floor thereof. A thermoswitch 718 is attached to a side wall of tray 714 to sense the temperature thereof and provide control signals for the system control network over leads 720. A heating element 722 connected to the control network by leads 724 is disposed in an aperture 726 in the floor of tray 714 for maintaining the same at an elevated temperature. Also communicating interiorly of tray 714 is an anhydrous developing-agent supply line 728 and a water feed tube 730.

45 The rear of chamber 702 is open to accept a developer belt drive assembly to be described below and is suitably sealed by a rectangular cover plate 731 attached as by screws (not shown) to the chamber walls. Cover plate 731 has a flat, rectangular blanket heating element 732 mounted on its inner surface, as shown in FIG. 26, to maintain the interior of the developing chamber at a substantially uniform elevated temperature for processing exposed copy sheets. The blanket heater 732 is connected by leads 734 to receive operating potential during the reproduction sequence. A thermoswitch 736 in the form of an elongated tube extends into the chamber from the inner surface of cover 730 along the left side thereof as visualized in FIG. 27 and is connected to the system control network via leads 738.

60 Disposed on the front portion of upper leg 706 of the developing chamber 702 is a generally flat, laterally disposed guide plate 740 supported through a pair of spaced elongated guides 739 and 741 by a pair of side support plates 742 and 744 extending from either side of the leg 706. Guides 739 and 741 are generally rectangular in section and are disposed laterally between plates 742 and 744 to preclude loss of a copy sheet as the same moves between roller sets 746-748 and

752-754. Carried between side plates 742 and 744 is a first set of parallel guide rollers 746, 748 which are aligned vertically with respect to each other and extend transversely across the front end of leg 706. Rollers 746 and 748 capture the advancing copy sheet and transport the same into the interior of the developing chamber 702 at a sealed entrance opening thereof indicated generally at 750.

The sealed opening 750 of leg 706 is formed by a second pair of guide rollers 752 and 754 disposed in like manner to that of rollers 746 and 748 and forming a seal therebetween. Two generally rectangular flat seal elements 756 and 758 constructed of any suitable material, such as rubber impregnated fiberglass, are attached to the upper and lower front edges of leg 706 by plates 760 and 762, respectively, so that they sealingly engage the front sides of rollers 752 and 754 to completely seal the opening or entrance of leg 706 while enabling the advancement of a copy sheet into the interior of the chamber. A pair of sprockets 764 and 766 are secured to the shafts of rollers 754 and 748, respectively, and cooperate with an endless drive chain 768 to impart rotational movement to both roller sets 746-748 and 752-754.

Drive chain 768 is constrained for movement about 764 and 768 as well as a set of take-up sprockets 770 and 772 affixed to the left side of the base portion 704 of chamber 702 as shown in FIGS. 26 and 27. Sprocket 772 is adjustable in a slot 774 to enable the take-up of any slack which might be present in the chain 768. Chain 768 also passes around a sprocket 776 secured to the shaft of a first roller 778 of a roller pair 778-780 of a sealed exit opening 782 on the front end of lower leg 708. Exit assembly 782 is constructed in like manner to that of entrance seal 750 described above and includes a pair of rectangular, flat seal members 782 and 784 attached to the leg 708 by plates 786 and 788, respectively, for tangential engagement with the front surface of the rollers 778 and 780 to seal the exit opening of leg 708 while enabling the passage of a developed copy sheet therefrom.

A gear 790 is attached to an exteriorly protruding right end of the shaft of roller 778 as visualized in FIG. 27 for cooperative engagement with a drive gear 792 of a suitable drive motor 794. Drive motor 794 is attached to the support leg 712 of the developing chamber 704 and causes the rotation of roller 778 and thus the movement of chain 768 for driving the remaining rollers described above. It is also noted that gear 792 engages gear 572 of conveyor 570 (FIG. 17) to drive the same during system operation. Also attached to the shaft of roller 778 is a second drive gear 796 disposed interiorly of leg 708 in a recess of generally rectangular configuration indicated at 798. Gear 796 is adapted to cooperate with an additional gear on a developer belt drive assembly indicated generally at 800 in FIG. 28.

The developer drive belt assembly 800 includes first and second like side plates 802 and 804 of generally U-shaped configuration and supporting therebetween in parallel relationship a plurality of rollers 806, 808, 810, 812, 814 and 816 supporting an endless belt 818 for movement over a generally U-shaped path shown in FIG. 28. Belt 818 may be constructed of any suitable material and is preferably made of a rubber impregnated fiberglass which is dimensionally stable with heat. A second endless belt 820 is constrained along a U-shaped path nested within belt 818 by a second set

of parallel rollers 822, 824, 826 and 828 which further cooperate with rollers 814 and 816 as shown. Belt 820 is formed of any suitable heat resistant porous material such as a heat treated cotton. A pair of horizontally disposed inclined rollers 830 and 832 are respectively mounted upon brackets 834 and 836 which are secured to side plates 802 and 804 of the developer belt assembly 800. Rollers 830 and 832 cooperate to maintain the belts in a centrally disposed lateral position as they are rotated through the chamber.

A thermally conductive, rectangular block 838 is disposed transversely between end plates 802 and 804 and defines a first aperture 840, for accommodating a cylindrical thermoswitch 842 (FIG. 26), and a second, somewhat larger aperture 844 for accommodating a cylindrical heating element 846 designed to maintain block 838 in an elevated temperature above that provided by the blanket heater 732 of the chamber cover 730. As shown in FIG. 26, thermoswitch 842 and heating element 846 protrude through the chamber walls of the upper leg portion 706 for accommodation within apertures 840 and 844 of block 838 after the developer belt assembly 800 has been installed within the chamber 702. Elements 842 and 846 are also connected by leads 848 and 850 respectively to the system control network. A gear 852 is affixed to the end of the shaft of roller 812 and engages gear 796 (FIG. 27) of developing chamber 702 to cause advancement of belts 818 and 820 through the chamber. Belts 818 and 820 are both driven through the shaft of roller 812 by the cooperative engagement of a pair of gears (not shown) attached to the upper ends of the shaft of roller 828 and 812 as viewed in FIG. 28.

As can be appreciated from FIG. 28, a copy sheet fed through the entrance opening 750 of chamber 702 will be captured between belts 818 and 820 as they pass over rollers 806 and 822, respectively, and will be constrained between the belts for movement over the illustrated U-shaped path. Since the interior of the chamber 702 is maintained at an elevated temperature during the development process, the dimensionally stable heat characteristics of belt 818 preclude the exertion of excessive pressure against the copy sheet surface as it passes between the nested belts of the developer belt assembly 800. At the same time, the porosity of belt 820 enables the copy sheet to be completely exposed to the developing agent present within the chamber 702 to effectuate the rapid development of the copy sheet as it traverses the development station.

While the microfiche duplicator according to the present invention may be utilized with equal efficacy with either an aqueous or anhydrous developer agent, as will be explained below, the preferred embodiment illustrated and described herein incorporates the use of anhydrous ammonia from a pressurized ammonia supply tank 900 (FIGS. 3 and 4) disposed within a retaining collar 902 in the floor of housing 12. Ammonia gas from tank 900 is supplied through a tube 904 to a T-fitting 906 supplying a pressure relief valve 908 and a pressure regulator 910. The pressure regulator 910 regulates the pressure of the ammonia gas and supplies the same through a solenoid valve 912, having a pair of electrical leads 914, to a conventional gas metering device 916. The output of metering device 916 communicates via tube 918 to the gas fitting 728 of the developing-agent receiving tray 714 as shown in FIG. 4. In this manner, a precisely metered flow of anhydrous am-

nia is supplied to the tray 714 under the control of solenoid 912 during the development of diazo copy films.

A liquid metering assembly indicated generally at 920 provides a precisely metered amount of liquid to the tray 714 through tube 730. The liquid metering assembly 920 is designed to supply water droplets to the tray 714 when anhydrous ammonia is utilized as the developing agent, but alternatively may be utilized to supply aqueous ammonia in which case the aforescribed anhydrous ammonia supply assembly is unnecessary. The construction and operation of the liquid metering assembly 920 is identical whether the liquid be water or aqueous ammonia with the exception that the liquid supply container will be vented to the atmosphere when water is supplied and will be vented interiorly of the development chamber 700 to provide a closed system when using an aqueous ammonia supply.

Referring to FIGS. 29 through 32, the liquid metering apparatus 920 includes a frame 922 secured to the frame of the duplicating apparatus and having mounted thereon an inverted liquid container 924. Communicating through the opening of container 924 is a flexible, liquid feed tube 926 contiguously joined with tube 730 shown in FIG. 4. Tube 926 from container 924 is disposed in a vertical position such that the liquid contained within the container 924 tends to flow therefrom through the tube 926 by gravity. A pair of generally triangular fluid control members 928 and 930 are pivotally secured at points 932 and 934, respectively, to the frame 922 and have secured at a corner thereof a protruding pin 936, 938 for pinching tube 926 against an upright flange of a generally L-shaped stop 940. Stop 940 is attached to frame 922 by a flat connecting member 942. The third corner of each of the triangular members 928 and 930 has a roller bearing 944, 946 mounted thereof for cooperation with a cam 948. Cam 948 is generally circular and defines a flat surface 950 causing the sequential reciprocation of triangular members 928 and 930, depicted in the sequence of FIGS. 29, 30 and 31, as the cam 48 is slowly rotated. A drive motor 952 is mounted to frame 922 and has its shaft connected to drive cam 948 for dispensing a preselected, metered amount of liquid from container 924.

CONTROL AND COOLING SYSTEM

Disposed within compartment 30 of the duplicator is a first blower 970 having an inlet hose 972 terminating at a louvered opening 974 in the side of the compartment 30. The outlet of blower 970 is supplied through branched hoses 976 and 978 to the area surrounding conveyor belt 570 and the copyboard plate 26, respectively, through ports 600 and 602 in frame plate 402 of the exposure and clearing assembly as illustrated in FIG. 17. An exhaust blower 980 has its inlet connected to hose 598 (FIG. 17) of the exposure lamp assembly and exhausts the heated air through an additional hose 982 to a second louvered opening 984 in compartment 30.

A power supply is housed within a compartment 986 for providing operating potential to the mercury vapor lamp 504 of the exposure lamp assembly. The exposure lamp power assembly may be of any suitable design and construction well known to those skilled in the art and thus will not be described in detail for the sake of brevity.

The duplicator of the present invention further includes a control network housed within cabinet 988 and constructed with conventional switching assemblies, such as relays, to provide the desired control sequence for operating the system. The particular circuit details of the control system for the duplicator of the present invention may be of any suitable design accomplishing the sequence to be described below. In view of the great number of variations in the details of the circuit control network, which are well known to those of ordinary skill in the art, no attempt will be made herein to describe any particular circuit in detail for the sake of brevity. However, the desired control sequence will be fully presented in accordance with the preferred mode of operation of the present invention as the description proceeds.

CONTROL SEQUENCE AND SYSTEM OPERATION

Prior to the beginning of a particular reproduction sequence, a roll 38 of diazo or vesicular film is inserted within compartment 30 and threaded through the film feed and cutting assemblies 44 and 46. The microfiche duplicator of the present invention is adapted to make copies using either of these film types dependent upon the position of a first selector switch 31 located within compartment 36. Diazo and vesicular lamps on panel 28 apprise the operator of the position of switch 31 when the duplicator is on. If a diazo film is used, and switch 31 is placed in its diazo selector position, the following sequence of events occurs as the "on" push button of panel 28 is depressed.

Initially, operating potential is fed to cooling blower 970, and all three heating elements 722, 732 and 846 of the developing assembly 700. In addition, the developer drive motor 794 is turned on causing the movement of the developer belts 818 and 820 as well as the clearing conveyor 570. As the temperature within the developing chamber 700 reaches approximately 160°F., as detected by thermoswitch 736, the vesicular heating element 846 is cut off, and the remaining heating elements 722 and 732 are appropriately cycled in accordance with the detected temperatures at thermoswitches 718 and 738. It is noted that the vesicular heater 846, which is adapted to raise the temperature of the thermally conductive block 838 to an elevated temperature of approximately 300°F., is utilized only to decrease the warm up time of the apparatus when energized in the diazo mode.

At the same time, motor 952 of the liquid metering assembly 920 is energized causing cam 948 to rotate for delivering a metered amount of water to the developing-agent receiving tray 714. Motor 952 may be run continuously at a slow speed, but is preferably cycled for operation by a suitable percentage timer (not shown). Also, solenoid valve 912 of the anhydrous ammonia supply system is energized causing a metered amount of anhydrous ammonia to be fed into the tray 714.

When the temperature within the developing chamber reaches approximately 160°F., the vesicular heater 846 is cut off, the exposure lamp 504 is supplied with operating potential, and the ready lamp on control panel 28 is turned on. A timer (not shown) is also energized at this time such that after a short interval of approximately three minutes, the cooling blower 980 of the exposure lamp assembly will begin operation. The

operation of the timing relay thus maintains blower 980 off until the mercury vapor lamp 504 has been energized sufficiently to vaporize the mercury contained therein and bring the lamp to full brilliance. The microfiche duplicator is thus placed in a stand-by mode ready to receive an original microfiche sheet for the making of a copy.

A second switch 33 in housing 36 may be placed in either of two positions corresponding to the use of roll or cut sheet copy film in the duplicator. With switch 33 in the sheet supply position, the sheet indicator lamp on control panel 28 is lit, and the film advance and cutting assemblies 44 and 46 are disabled to preclude inadvertent advance of the film from roll 38. With switch 33 in the roll feed position, an operator may depress either the single or multiple selector push buttons, the number of multiple copies being preselectable by the setting of the counter of control panel 28. If the single copy push button is depressed, motor 90 of the film feed and cutting assemblies will become energized causing the rotation of cams 100 and 150. A precisely measured length of copy film will thus be fed from the supply roll 38 and is thereafter severed by blade 130, so as to fall atop the original microfiche sheet which has been previously inserted over the copyboard plate 26.

Cam 100 will continue to traverse a 360° arc engaging arm 118 of microswitch 114 to deenergize motor 90 and bring the cam 100 to rest. Actuation of microswitch 114 by cam 100 also causes the energization of the DC drive motor 326 of the copyboard assembly, whereupon the same is moved forward at a rate dependent upon the setting of the exposure dial on control panel 28. Additional microswitches 608 and 604 of the exposure and clearing assembly coact with protrusions 214 and 216 of the copyboard to detect the limits of movement thereof as the reproduction sequence progresses. Specifically, microswitch 608 detects the limit of forward movement of the copyboard causing drive motor 326 to be reversed. As motor 326 rotates in the reverse direction, the copyboard is rapidly returned to the front of the duplicator. The copy sheet thereafter continues its advancement through the developing chamber and back toward the front of the duplicator where it is conveniently delivered to the receiving tray 34. The original microfiche sheet is maintained on the copyboard and is returned therewith for the making of additional copies if so desired.

If the multiple copy selector button is depressed on control panel 28, the above sequence is repeated for the desired number of copies, with the copyboard carrying the original sheet back and forth along its linear path of travel as each exposed copy sheet is cut and fed through the exposure and developing stations.

To further clarify the operation of the microfiche duplicator of the present invention, reference will now be made to the diagrammatic views of FIGS. 20 through 25. Referring to FIGS. 20 and 21, at the start of a reproduction sequence, an original microfiche sheet O is placed atop the copyboard plate 26 between the fixed left stop 224 (FIG. 1) and the retracted right hand stops 292 and 294. As the operator inserts the original microfiche sheet on to the copyboard, lever 262 is depressed downwardly causing front stops 244 and 246 to be retracted flush with the copyboard surface. The leading edge of the original sheet is thereafter located underneath the thin plastic separator sheet 242 and against the front side of the compressible sponge-like

element 240. Release of lever 262 thereafter returns the front stops 244 and 246 to their upright positions shown in FIG. 1 thereby capturing the original sheet in its proper longitudinal position on the copyboard.

A measured and cut length of copy film C from supply roll 38 is thereafter dropped onto the copyboard approximately three-eighths of an inch forward of the stops 244 and 246 and between the left and right stop members. Thus, the copy sheet drops onto the copyboard with its leading edge above the plastic separator element 242 enabling positive separation of the copy and original sheets after exposure.

As the copyboard begins its forward travel, the cammed right hand stop members 292 and 294 move toward the fixed left stop 224, as controlled by roller 308 and cam 310 (FIG. 15). Stops 292 and 294 thus move both the original and copy sheets against stop 224 to provide positive lateral registration therebetween.

Further forward travel of the copyboard causes the inclined leading edge 340 thereof to engage the soft pressure roller 414 causing the same to rotate clockwise as visualized in FIGS. 20 and 21. The frictional engagement of carrier plate 418 with pressure roller 414 causes the same to rotate clockwise so as to lower the rubber drag elements 428 and 430 against the copyboard surface as shown in FIG. 21. Nose member 432 also moves downwardly against the copyboard so as to flatten the film and remove the curl in the copy sheet to provide accurate registration as the copyboard advances. Continued movement of the copyboard causes the rubber drag elements 428 and 430 to engage the copy sheet C to slide the same against stops 244 and 246, completing the registration sequence.

Both the cammed right hand stops 292 and 294 and stops 244 and 246 maintain their upright positions until the copy and original sheets are captured by the pressure roller 414. Thereafter, and in response to continued forward movement of the copyboard assembly, the cammed right hand stops 292 and 294 are retracted to their rest positions to assure clearance with the end of the pressure roller 414. Similarly, the forward movement of the copyboard causes the engagement of arm 250 with stationary cam 330 for retracting stops 244 and 246 to their flush or nested positions within the top surface of the copyboard so that they will pass underneath roller 414 without damaging the same.

As the registered original and copy sheets pass under pressure roller 414, a compressive force is exerted thereagainst causing both sheets to be maintained in firm contact with each other and with the copyboard plate 26 for accurate exposure. As shown in FIG. 22, the ultraviolet radiation from lamp 504 is directed through a suitable slit aperture having a width somewhat less than the flat section of the pressure roller 414 compressed against the glass. In this manner, the copy sheet C is securely held over original sheet O for assuring distortionfree exposure of the copy as the copyboard continues its forward travel.

As the copy sheet C is exposed, and passes beyond roller 414, it is separated from the original sheet O by the pick off plate 450 shown diagrammatically in FIGS. 23 through 25. As described above, the original sheet O is placed in position on the copyboard so that the leading edge thereof is below the plastic separator sheet 242. Also, the copy sheet C is aligned with the original such that its leading edge is above the separa-

tor sheet 242 as shown. When the copyboard moves forward beneath the pressure roller 414, the soft foam material 240 supporting the separator sheet 242 is compressed so that good contact between the master or original and copy sheets is attained. As the separator 242 exits from the pressure roller 414, the foam sheet 240 returns to its original shape causing the leading edges of the original and copy sheets to be slightly separated. Further forward travel causes the roller bearing 454 of the pick off plate 450 to ride into recess 336 of cam 334 enabling the pick off plate to be pivoted against the separator sheet 242. As plate 450 moves downwardly, the tapered leading edge thereof compresses the foam support sheet 240 enabling the apex of the pick off plate to ride under the leading edge of the copy sheet C. As the copyboard continues its forward travel, the copy sheet is caused to ride up on the pick off plate 450 with cam 334 acting through roller 454 to raise the pick off plate away from the copy board surface to preclude damaging the original sheet as it moves thereunder. The original sheet remains under the separator sheet 242 while the copyboard finishes its forward travel and thereafter returns to its start or loading position shown in FIG. 1.

Referring again to FIG. 22, the separated copy sheet C is passed above pick off plate 450 and is thereafter guided between roller sets 746-748 and 752-754 into the developing chamber 800. The advancing copy sheet is thereafter captured between belts 818 and 820 within the chamber 700 for transporting the copy sheet and developing the exposed image therein. As noted above, if the copy sheet is a diazo film the copyboard will be exposed to ammonia, water vapor and an elevated temperature of approximately 160°F., causing the development of the exposed image. If the copy sheet, on the other hand, is a vesicular film, the same will be developed by 300° temperature of block 838 in the upper leg of the developing chamber. Of course, in the vesicular mode, the anhydrous ammonia solenoid valve will be deenergized, as will be the liquid metering assembly 920, such that the copy sheet is merely exposed to heat for affecting development thereof. The developed copy sheet is passed from the lower leg of the development chamber through rollers 778 and 780 and onto conveyor belt 570.

Conveyor belt 570 transports a developed diazo copy to the receiving tray 34 and also acts as a clearing station for a developed vesicular copy. In the vesicular mode, preselected by switch 31, solenoid 544 is energized to rotate reflector element 534 to the position shown in dashed lines in FIG. 22. With reflector element 534 swung to its retracted position, light from lamp 504 passes through heat filter 487 and shines on the upper surface of conveyor 570. As the developed vesicular copy sheet passes under the lamp assembly 470, the light from lamp 504 causes the same to be cleared, thus fixing the exposed and developed image of the original microfiche. It can be appreciated from the above, that both diazo and vesicular film types may be used in the microfiche duplicator of the present invention by merely repositioning switch 31 to place the developing chamber in a diazo mode (whereby the copy sheet is exposed to ammonia, water vapor and a substantially uniform temperature of approximately 160°F.) or a vesicular mode (whereby the copy sheet is exposed to a temperature of approximately 300°F.). Further, in the diazo mode, reflector assembly 470 is

closed, shielding the conveyor 570 from the ultraviolet radiation of lamp 504, and in the vesicular mode is open to provide clearing light for the developed copy.

In addition to the above, in the diazo mode, a precise amount of liquid is fed from container 924 to the developing chamber 700 by the liquid metering assembly 920. In operation, as cam 948 rotates, the upper pinch roller 938 is swung away from supply tube 926 opening the same for the gravity flow of liquid down to the lower pinch roller 936 as shown in FIG. 29. As the cam continues to rotate, the upper pinch roller will close, trapping a precise amount of liquid between the upper and lower rollers 938 and 936, as depicted in FIG. 30. Continued rotation of the cam 948 causes the lower pinch roller to open while the upper roller remains closed, permitting the trapped liquid to flow through the tube to the developing-agent receiving tray 714. As can be appreciated, the amount of liquid to be metered can be readily controlled by the spacing between pinch rollers 936 and 938 as well as by the speed of the cam 948 driven by motor 952.

The microfiche duplicator of the present invention is thus believed to represent a material advance in the microcopy art, especially in view of its flexibility, versatility and efficiency in design and operation. As noted above, the duplicator provides a number of distinct advantages in that diazo or vesicular films may be used interchangeably, that the copy sheet is exposed and developed after the same is cut from roll 38 thereby avoiding waste, that a single mercury vapor lamp is used for exposing diazo and vesicular copy films as well as for clearing vesicular films, that master and copy sheets are automatically registered, both laterally and longitudinally, in response to movement of the copyboard, and that the overall combination is compact and requires a minimal amount of power.

Inasmuch as the present invention is subject to many variations, modifications and changes in detail, it is intended that the foregoing description be interpreted as illustrative of a preferred mode and not in a limiting sense.

What is claimed is:

1. A microfiche duplicator comprising a frame, a copyboard movable on said frame between loading and exposing stations and supporting an original film sheet and a copy sheet in superposed relationship, register means coupled with said copyboard and responsive to movement of said copyboard to said exposing station for registering said copy sheet with said original sheet, means mounted on said frame at said exposure station to expose said copy sheet through said original sheet, developing means for said exposed copy sheet, and means separating said exposed copy sheet from said original sheet and transporting the same to said developing means.
2. The invention as recited in claim 1, further including clearing means selectively actuatable to clear the unexposed areas of a developed vesicular copy sheet, and wherein said developing means includes means operative in first and second modes for developing diazo and vesicular copies, respectively.

3. The invention as recited in claim 1, wherein said developing means includes a closed chamber having sealed inlet and outlet openings accepting said copy sheet for passage therethrough, first means heating said chamber to a first elevated temperature and supplying ammonia and water vapor to the interior thereof, second means heating said chamber to a second elevated temperature greater than said first elevated temperature, and selector means having first and second modes for activating said first and second means, respectively. 10

4. The invention as recited in claim 1, wherein the speed of movement of said copyboard through said exposure station is adjustable to control the degree of exposure of said copy sheet through said original sheet. 15

5. The invention as recited in claim 1, wherein said copyboard is linearly movable on said frame. 20

6. The invention as recited in claim 1, wherein said register means includes first and second stop means disposed on first and second opposite sides of said copyboard and movable relative to each other in response to movement of said copyboard. 25

7. The invention as recited in claim 6, wherein said register means further includes third and fourth stop means disposed on third and fourth opposite sides of said copyboard and movable relative to each other. 30

8. The invention as recited in claim 1, wherein said exposure means includes a source of ultraviolet radiation and roller means mounted in superposition thereof, and wherein said copyboard includes an ultraviolet transmissive plate supporting said original and copy sheets and movable between said roller means and said ultraviolet source whereby said original and copy sheets are held against each other and said transmissive plate by said roller means as said copyboard moves past said ultraviolet source. 35

9. The invention as recited in claim 8, further including hold-down means responsive to engagement of said copyboard with said roller means for holding said copy sheet against said original sheet as said copyboard moves toward said exposing station. 40

10. The invention as recited in claim 1, wherein said developing means includes a generally U-shaped closed chamber having the legs thereof disposed in horizontal superposition on said frame, said chamber having sealed opening means on the end of each said leg adapted to pass said copy sheet therethrough, the upper leg of said chamber being disposed adjacent said exposing station for receiving an exposed copy sheet. 45

11. The invention as recited in claim 10, further including conveyor means disposed on said frame below said exposure station and adjacent the lower leg of said chamber for transporting said developed copy sheet from said developing means to a receptacle under said loading station. 50

12. The invention as recited in claim 11, wherein said exposing means includes a source of ultraviolet radiation mounted on said frame below the path of travel of said copyboard and above said conveyor means and further includes reflector means under said ultraviolet source, said reflector means movable between a closed position shielding said conveyor means from exposure to said ultraviolet radiation and an open position exposing said conveyor means to said ultraviolet radiation whereby a developed copy sheet of vesicular film may 55

be cleared as it is transported beneath said ultraviolet source on said conveyor means. 60

13. The invention as recited in claim 10, wherein said developing means includes first and second continuous conveyor belts each traversing a generally U-shaped path with said second conveyor belt nested within the first and carrying therebetween said copy sheet from the open end of said upper leg to the open end of said lower leg, said first conveyor belt being dimensionally stable with respect to heat and said second conveyor belt being porous. 65

14. The invention as recited in claim 13, wherein said first conveyor belt is constructed of rubber impregnated fiberglass and said second conveyor belt is constructed of cotton. 70

15. The invention as recited in claim 10, wherein said developing means further includes a developing-agent receiving tray in the floor of said chamber. 75

16. The invention as recited in claim 15, wherein said developing means further includes liquid supply means connected with said developing-agent receiving tray to supply a metered amount of liquid thereto. 80

17. The invention as recited in claim 16, wherein said liquid supply means includes a liquid container, a flexible tube connecting said container with said developing-agent receiving tray and having a portion thereof aligned vertically, and fluid control means sequentially closing said vertical portion of said flexible tube at first and second spaced points therealong. 85

18. The invention as recited in claim 17, wherein said container contains aqueous ammonia, and wherein said liquid supply means includes means venting said container interiorly of said developing chamber. 90

19. The invention as recited in claim 17, wherein said container contains water, and wherein said developing means further includes a source of anhydrous ammonia communicating interiorly of said developing chamber at said developing-agent receiving tray. 95

20. The invention as recited in claim 10, wherein said developing chamber contains a first heating element maintaining the interior of said chamber at a substantially uniform temperature above room temperature, a second heating element disposed within the upper leg of said chamber maintaining the interior of said upper leg at a temperature above that provided by said first heating element, and a third heating element disposed in a developer-agent receiving tray in the floor of said chamber. 100

21. The invention as recited in claim 1, further including film supply means on said frame laterally adjacent said copyboard for feeding a preselected length of copy film over said copyboard and cutting the same whereby said cut sheet of copy film falls onto said copyboard in approximate registration with said original sheet. 105

22. The invention as recited in claim 21, wherein said film supply means includes a roll of copy film, roller means capturing the end of said film roll, and drive means imparting rotary motion to said roller means to advance said end of said film roll a preselected amount. 110

23. The invention as recited in claim 22, wherein said drive means includes a drive wheel operatively connected with said roller means and rotating the same to impart said preselected film advance upon completion of a single revolution of said drive wheel. 115

24. The invention as recited in claim 23, wherein said film supply means includes a cutting assembly, and wherein said drive means further includes a cam engaging said cutting assembly to cut said advancing end of said film roll after said preselected length has been ad-

vanced from said roll.

25. The invention as recited in claim 1, including means for cooling said copyboard and said exposing means.

UNITED STATES PATENT OFFICE
CERTIFICATE OF CORRECTION

Patent No. 3,836,252 Dated September 17, 1974

Inventor(s) A. F. Touchette, Nils L. Hakanson

It is certified that error appears in the above-identified patent and that said Letters Patent are hereby corrected as shown below:

Column 2, line 40, "FIG. 7" should be --FIG. 6--.

Column 5, line 36, "on" should be --in--.

Column 5, line 55, "the" should be --as--.

Column 8, line 66, "members 164" should be --member 264--.

Column 9, line 18, "roate" should be --rotate--.

Column 10, line 26, "224" should be --244--.

Column 17, line 18, change "acqueous" to --aqueous--.

Column 24, line 59, change "menas" to --means--.
